CN 2842604 Y 11/2006
(Continued)*Primary Examiner* — Ian Simmons*Assistant Examiner* — Carissa C Fitts(74) *Attorney, Agent, or Firm* — Armstrong Teasdale LLP(57) **CLAIM**

The ornamental design for a glow light, as shown and described.

DESCRIPTION

FIG. 1 is a front perspective view of a glow light in accordance with an embodiment.

FIG. 2 is a rear perspective view of the glow light shown FIG. 1.

FIG. 3 is a front view of the glow light shown in FIG. 1, the rear view being a mirror image thereof.

FIG. 4 is a right side view of the glow light shown in FIG. 1.

FIG. 5 is a left side view of the glow light shown in FIG. 1.

FIG. 6 is a top view of the glow light shown in FIG. 1; and, FIG. 7 is a bottom view of the glow light shown in FIG. 1. The broken lines are included for the purpose of illustrating an eye that forms no part of the claimed design.
